UNITED STATES PATENT OFFICE

FRED S. BOLTZ, OF MANSFIELD, MASSACHUSETTS

TANK

Application filed January 20, 1928. Serial No. 248,146.

The invention relates to an improvement in tanks. It is especially intended for application to tanks which are intended for use as containers for hot water or other liquids or substances which have a tendency to corrode metal. When the tank is made entirely of sheet steel or other corrodible metal, it soon becomes corroded thereby causing the tank to leak and discoloring the liquid in the tank.

10 The use of non-corrodible metal for the entire tank is very expensive if the sheets of which the tank is made are sufficiently thick to give the necessary strength. It has, therefore, become common to make the tank with an inner shell or lining of non-corrodible metal and with an outer or reenforcing shell of steel or other relatively cheap metal which is corrodible.

One object of the present invention is to 20 provide a form of joints which will be non-corrodible and is easily made.

Another object of the invention is to provide an interlocking joint for the meeting edges of the sheets which form the body of 25 the container.

Another feature is to provide a special reenforcing strip on the outside of the tank to cover the side joint.

The invention will be fully understood 30 from the following description when taken in connection with the accompanying drawings and the novel features thereof will be pointed out and clearly defined in the claims at the close of this specification.

35 Fig. 1 is a longitudinal section of a tank embodying the invention.

Fig. 2 is a section on line 2—2, Fig. 1.

Fig. 3 is an enlarged detail sectional view showing the reenforcing strip in combination 40 with the inner and outer shell.

Referring to the drawings, there is shown at 10 a tubular outer or reenforcing shell of the tank which may be made of steel or other corrodible sheet metal and at 11 is shown an 45 inner shell of non-corrodible sheet metal, preferably brass, copper or Monel. Each of these shells is made of sheet metal rolled into cylindrical form and having a longitudinal union or joint at the meeting edges. The 50 ends of the tank are provided respectively with two heads B, C, preferably dished inward to enable workmen to make a tight joint easily from outside of the tank. At D is shown a heating element connected with the head C in any suitable manner. Any suitable 55 heating element may be used for this purpose as this forms no part of the invention. The longitudinal side edges of the inner shell 11 of non-corrodible metal abut each other and are formed with outwardly turned lips or flanges 16 which preferably flare somewhat away from each other as shown in Fig. 3, leaving a V-shaped notch between them. The side edges 17 of the outer or reenforcing shell 10 are beveled as shown in Fig. 3 and flare 60 away from each other. The inner corners 9 of said reenforcing shell engage the said flange 16, 16 of the lining shell. There is thus formed a sort of wedge-shaped or inwardly tapering recess between the adjacent 65 edges of said outer shell and a V-shaped notch between the flanges 16, 16 of the inner shell. The adjacent edges of the reenforcing shell and of the non-corrodible inner shell are all united together as shown at 18 by 70 welding or brazing or other non-corrodible material adapted to fill the said recess between the adjacent ends of the outer shell and of the V-shaped recess between the two flanges 16, 16 of the inner shell and unite the 75 parts together. The filling is flaring sided in cross section as shown in Fig. 3, the broad side or head of the wedge being on the outer side. In order to further protect the joint against fracture there is provided a longitudinal covering strip 19 which may be of 80 steel or other suitable metal which covers the outer face of the block of filling 18 and this strip overlaps the adjacent sides of the outer metal shell 10 far enough to cover the entire 85 joint. This strip is secured to the outer face of the shell 10 by any suitable means, preferably by welding or soldering as shown at 20.

What I claim is:

1. A sheet metal tank comprising an inner tubular shell formed of a sheet of non-corrodible metal and a reenforcing outer metal shell, the adjacent side edges of the sheet forming the inner shell having flanges whose 90

100

adjacent faces flare away from each other, the adjacent side edges of said outer shell engaging said flanges of the inner shell and flaring away from each other, thereby forming a flaring-sided groove between the edges of said outer shell, and said groove having a filling of solder or the like which unites together said outer shell and inner shell by a water tight joint and a covering strip which extends lengthwise of the shell and covers the said filling and laps over onto the periphery of the outer shell.

2. A tank comprising an outer shell consisting of sheet metal formed into a tube, a lining shell of non-corrodible sheet metal, the adjacent edges of the outer shell being spaced apart from each other, the adjacent edges of the lining shell being formed with flanges which extend into the space between the edges of the outer shell and a uniting substance in the space between the edges of the outer shell which unites the two shells together along the said adjacent edges.

3. A tank comprising an outer shell consisting of a sheet of metal shaped to substantially tubular form with a space between the adjacent longitudinal edges of the sheet, a lining shell of sheet metal formed into a tube whose adjacent longitudinal edges are formed with flanges which project into the space between the adjacent edges of the outer shell and a uniting substance in the space between the edges of the outer shell which unites the two shells together along the said adjacent edges.

4. A tank comprising an outer shell consisting of a sheet of metal formed into a tube with a longitudinal opening between the adjacent longitudinal edges of the sheet, a lining shell of metal formed into a tube whose adjacent longitudinal edges are formed with flanges which project into the space between the adjacent edges of the outer shell, a uniting substance in the space between the edges of said shells which unites the two shells together along the said adjacent edges, and a covering strip which extends lengthwise of the outer shell and covers the said uniting substance and laps over onto the periphery of said outer shell.

5. A tank comprising an outer shell consisting of a sheet of metal shaped to substantially tubular form with a longitudinal opening between the adjacent edges of the sheet and a lining shell of sheet metal formed into a tube whose adjacent edges are formed with flanges which project into the space between the adjacent edges of the outer shell, the adjacent faces of the flanges of said inner shell flaring away from each other forming a flaring sided groove, said groove having a filling substance which unites together said outer shell.

6. A tank having a body portion comprising two metallic shells, one forming a lin-

ing for the other, each shell consisting of sheet metal rolled into the form of a split tube, the side edges of both tubes having interengaging portions and spaces between said interengaging portions and a bonding substance which enters the said spaces and forms a common bond to unite together both tubes and the side edges of each tube.

In testimony whereof I affix my signature.
